ADJUSTABLE CHAIRS

Peter S. Fletcher, Boynton Beach, Fla., assignor to Anton Lorenz, Boynton Beach, Fla.

Application February 9, 1956, Serial No. 564,559

5 Claims. (Cl. 155—106)

This invention relates to adjustable chairs and particularly to those in which the seat and back rest may be adjusted between sitting positions and tilted positions.

An object of the invention is to provide an improved adjustable and comfortable chair of this type which, when the seat and back rest are adjusted into their tilted positions, will advance and elevate a leg rest from a normal, inactive position beneath the seat to a position in front of said seat, which uses simple, compact and relatively inexpensive linkage for operating the leg rest, and which has approximately the overall dimensions of an ordinary chair.

Other objects and advantages will be apparent from the following description of two examples of the invention and the novel features will be particularly pointed out hereinafter in connection with the appended claims.

In the accompanying drawings:

Fig. 1 is a side, sectional elevation of a chair constructed in accordance with the invention, the section being taken from front to rear of the chair just inside the arm nearest the observer, and the chair having the seat and back rest in sitting positions;

Fig. 2 is a similar view but with the seat and back rest in tilted positions;

Fig. 2a is a schematic diagram illustrating the basic linkage employed to support and operate the leg rest;

Fig. 3 is a view similar to Fig. 1, but employing a different linkage to support and position the leg rest;

Fig. 4 is a view similar to Fig. 3, but with the seat and back rest in their tilted positions, and

Fig. 4a is a schematic diagram illustrating the lazy tong linkage employed in Figs. 3 and 4.

In the example of the invention illustrated in Figs. 1, 2 and 2a, the chair includes a support 1 having side arms 2 and a seat 4, and back rest 5 between the side arms. The seat is pivoted at its rear part on a pivot rod 6 carried by the support, and the back rest is also pivoted near its bottom part on the same rod 6. The back rest depends below the rod 6 and is pivoted at its lower end by pin 7 to one end of an actuating link, one at each side of the seat. A set of linkage is provided at each side of the seat for supporting a leg rest 9 that is disposed beneath the forward part of the seat when the seat and back rest are in their sitting positions, as shown in Fig. 1.

Each set of linkage includes four or more pairs of links. Links 10 and 11, which are hinged together at 12, form the first pair of links, and the link 10 of this pair is pivoted by pin 13 to the seat 4. Links 14 and 15, which are hinged together at 16 form the second pair of links, and link 14 is pivoted by pin 17 to the seat 4. Links 18 and 19, which are hinged together at 20, form a third pair of links, and link 18 is pivoted by pin 21 to the leg rest 9. The link 19 is pivoted by pin 22 to an end of link 15. Links 23 and 24, which are hinged together at 25, form a fourth pair of links, and link 23 is pivoted by pin 26 to the leg rest 9. The link 24 is pivoted by pin 27 to an end of link 11.

The links 10 and 15 cross each other, and where they cross they are pivoted together by pin 28. The links 10 and 18 also cross each other, and where they cross they are pivoted together by pin 29. Links 18 and 24 also cross, and where they cross they are pivoted together by pin 30. The link 15 extends rearwardly of

2

the chair from its hinge 16, and the link 18 also extends rearwardly from the leg rest at least as far towards the rear of the chair as any of the other links extend rearwardly of the chair. A guiding link 31, normally approximately upright, is pivoted at its upper end by pin 32 to the support and at its lower end by pin 33 to an intermediate part of the actuating link 8. The forward end of link 8 is pivoted by pin 34 to an intermediate part of link 10. The four pairs of links form a lazy tong device, one at each side of the seat, which is supported at one end by the seat 4 and at its other end supports the leg rest 9. When the back rest is rocked rearwardly into its tilted position, shown in Fig. 2, the actuating links 8 will be moved endwise and forwardly of the chair to actuate the lazy tong devices to which they are connected, and this will advance and elevate the leg rest 9 to a position in front of the seat 4. When the back rest returns to its upright or sitting position, shown in Fig. 1, the links 8 will be moved endwise, to the rear of the chair, and actuate the lazy tong devices back to the retracted positions shown in Fig. 1. When actuating link 8 was moved forwardly to advance the lazy tong device, guiding link 31 rocked clockwise and caused link 10 to rise, which because of its connection to the seat, caused the forward part of the seat to rise.

In the example of the invention shown in Figs. 3, 4 and 4a, the chair has the support 1, side arms 2, seat 4, back rest 5, pivot rod 6, pin 7, actuating links 8 and leg rest 9, as explained in connection with Figs. 1 and 2. At each end of the seat there are four pairs of links, the pairs at each side forming a lazy tong device. Links 35 and 36 (Fig. 4a), which are hinged together at 36', form the first pair of links, and link 35 is pivoted by pin 37 to the support 1. Links 38 and 39, which are hinged together at 40, form a second pair of links, and link 38 is pivoted by pin 41 to the seat 4. Links 42 and 43, which are hinged together at 44, form a third pair of links, and link 42 is pivoted by a pin 45 to leg rest 9. Links 46 and 47, which are hinged together at 48, form a fourth pair of links, and link 46 is pivoted by a pin 49 to the leg rest 9. Ends of links 36 and 43 are pivotally connected by pin 50, and ends of links 39 and 47 are pivotally connected by pin 51. The links 35 and 39 cross each other, and at the crossing are pivoted together by pin 52. Links 36 and 47 also cross each other, and at the crossing are pivoted together by pin 53. Links 42 and 47 cross each other, and at the crossing are pivoted together by pin 54.

A guiding link 55 at each side of the seat is pivoted at one end by pin 56 to the seat 4 and at its other end by pin 57 to an intermediate part of the adjacent link 35. The forward end of the actuating link 8 is pivoted by pin 52 to the pairs of links at the crossing of links 35 and 39. The leg rest 9 is disposed beneath the forward part of the seat 4 when the back rest is in its upright or sitting position, as shown in Fig. 3. When the back rest is rocked rearwardly into the tilted position shown in Fig. 4, it operates actuating links 8 forwardly of the chair and causes an advancing operation of the lazy tong devices to advance and elevate leg rest 9 to a position in front of the seat, as shown in Fig. 4. At the same time the link 35, which is pivoted to the support, carries the lazy tong linkage upwardly and through links 38 and 55, raises the forward part of the seat into its tilted position shown in Fig. 4. When the back rest is returned to its upright position shown in Fig. 3, it moves actuating links 8 rearwardly, which operates the lazy tong devices to the retracted positions shown in Fig. 3, during which links 38 and 55 lower the forward part of the seat. The retraction of the lazy tong devices returns the leg rest to the inactive position beneath the forward part of the seat, as shown in Fig. 3.

It will be observed from the drawings that the quadrilaterals of linkage of each lazy tong device are arranged in tandem and start first rearwardly and at the other end progress forwardly, that the links of different pairs cross each other and at the crossing are pivoted together so that some of the links are parts of two successive quadrilaterals of links, and that at least one of the links that is pivoted to the leg rest at each side of the seat, extends from the leg rest rearwardly of the chair when the leg rest is beneath the seat, at least approximately as far in the chair as any of the other links extend rearwardly, as shown in Figs. 1 and 3. It will also be noted that the successive quadrilaterals of links in each device are articulately connected to one another only where the links of different pairs cross one another and are there pivoted to one another.

It will be understood that various changes in the details and arrangements of parts which have been herein described and illustrated in order to explain the nature of the invention, may be made by those skilled in the art within the principle and scope of the invention as expressed in the appended claims.

I claim:

1. An adjustable chair comprising a support, a seat, a back rest, said seat and back rest being carried by said support for movement between sitting positions and tilted positions, a leg rest disposed beneath the forward part of the seat, a plurality of pairs of links at each side of the seat, the links of each pair being hinged to one another, and said pairs being articulately connected to form a lazy tong device at each side of the seat, one link of the first two pairs of links being pivoted to one of said seat and said support, the other link of at least one of said first two pairs extending rearwardly from its hinge to the said one link of that pair, one link of each of two other pairs being pivoted to said leg rest and the other links of these pairs being pivoted to the other links of said first two pairs, said links crossing and pivoted to each other at three places, and an actuating means operably connected with said back rest and operable when the back rest is moved between said positions and connected to a link of said device to actuate it to advance and elevate said leg rest when the back rest is moved into its tilted position, and to retract and lower said leg rest when said back rest is returned to its sitting position.

2. An adjustable chair comprising a support, a seat, a back rest, said seat and back rest being carried by said support for movement between sitting positions and tilted positions, a leg rest disposed beneath the forward part of the seat, a plurality of pairs of links at each side of the seat, the links of each pair being hinged to one another, and said pairs being articulately connected to form a lazy tong device at each side of the seat, one link of each of the first two pairs of links being pivoted to said seat, the other link of at least one of said first two pairs extending rearwardly from its hinge to the said one link of that pair, one link of each of two other pairs being pivoted to said leg rest and the other links of these pairs being pivoted to the other links of said first two pairs, said links crossing and pivoted to each other at three places, an actuating link operably connected to said back rest and operable when the back rest is moved between said positions and connected to a link of said device to actuate it to advance and elevate said leg rest when the back rest is moved into its tilted position, and to retract and lower said leg rest when said back rest is returned to its sitting position, and a guiding link pivoted at one end to said support and at its other end to the actuating link remote from its connection to said back rest.

3. An adjustable chair comprising a support, a seat, a back rest, said seat and back rest being carried by said support for movement between sitting positions and tilted positions, a leg rest disposed beneath the forward part of the seat, a plurality of pairs of links at each side of

the seat, the links of each pair being hinged to one another, and said pairs being articulately connected to form a lazy tong device at each side of the seat, one link of each of the first two pairs of links being pivoted to one of said seat and said support, the other link of at least one of said first two pairs extending rearwardly from its hinge to the said one link of that pair, one link of each of two other pairs being pivoted to said leg rest and the other links of these pairs being pivoted to the other links of said first two pairs, said links crossing and pivoted to each other at three places, at least one of said links which is pivoted to said leg rest extending rearwardly as far as any one of the other links of the first two pairs when the leg rest is beneath the seat, and an actuating means operably connected with said back rest and operable when the back rest is moved between said positions and connected to a link of said device to actuate it to advance and elevate said leg rest when the back rest is moved into its tilted position, and to retract and lower said leg rest when said back rest is returned to its sitting position.

4. An adjustable chair comprising a support, a seat and a back rest adjustable between two positions on said support, a leg rest normally disposed beneath the forward part of said seat, a lazy tong device at each side of said seat and supporting said leg rest at one end thereof, each said device having a plurality of pairs of links, the links of each pair being hinged together, one link of each of the first two pairs being pivoted to one of said seat and said support, one link of each of the last two pairs being pivoted to said leg rest, those links of each of the first two pairs which are not directly pivoted to one of said seat and support extending one rearwardly and one forwardly from its hinge to the other link of the pair, and pivoted to those links of the last two pairs which are not directly pivoted to said leg rest, and means operable from said back rest and having an actuating link connected to at least one of said devices for causing an operation of said devices to advance and elevate said leg rest to a position in front of said seat when the back rest is moved into a tilted position and to return said leg rest to a position beneath said seat when the back rest returns to its other position.

5. An adjustable chair comprising a support, a seat and a back rest adjustable between two positions on said support, a leg rest normally disposed beneath the forward part of said seat, a lazy tong device at each side of said seat and supporting said leg rest at one end thereof, each said device having a plurality of pairs of links, the links of each pair being hinged together, one link of each of the first two pairs being pivoted to one of said seat and said support, one link of each of the last two pairs being pivoted to said leg rest, those links of each of the first two pairs which are not directly pivoted to one of said seat and support extending one rearwardly and one forwardly from its hinge to the other link of the pair, and pivoted to those links of the last two pairs which are not directly pivoted to said leg rest, at least one link of each of the first two and last two of said pairs crossing and being pivoted to a link of another pair, and means operable from said back rest and having an actuating link connected to at least one of said devices for causing an operation of said devices to advance and elevate said leg rest to a position in front of said seat when the backrest is moved into a tilted position and to return said leg rest to a position beneath said seat when the back rest returns to its other position.
